UNDERWATER SONAR APPARATUS

Forrest L. Murdock, Tulsa, Okla., assignor to Fishmaster Products, Inc., Tulsa, Okla.

Filed May 18, 1973, Ser. No. 361,531

Term of patent 14 years

Int. Cl. D10—99

U.S. Cl. D10—46

Fig. 1

Fig. 2

Fig. 3

Fig. 4

Fig. 5

Fig. 6

FIG. 1 is a top plan view of an underwater sonar apparatus showing my new design;

FIG. 2 is an elevational view of one side;

FIG. 3 is a bottom plan view;

FIG. 4 is an elevational view of the other side;

FIG. 5 is an elevational view of the forward end; and

FIG. 6 is an elevational view of the rearward end thereof.

I claim:

The ornamental design for an underwater sonar apparatus, substantially as shown and described.
